UNITED STATES PATENT OFFICE.

FRANKLIN S. MARR, OF CANTON, ILLINOIS.

DESIGN FOR A PUZZLE.

54,759.

Specification for Design.

Patented Mar. 23, 1920.

Application filed May 21, 1919. Serial No. 298,783. Term of patent 3½ years.

To all whom it may concern:

Be it known that I, FRANKLIN S. MARR, a citizen of the United States, residing at Canton, in the county of Fulton and State of Illinois, have invented a certain new, original, and ornamental Design for a Puzzle, of which the following is a specification, reference being had to the accompanying drawing, forming a part thereof.

I claim:

The ornamental design for a puzzle, as shown.

In testimony whereof I hereunto affix my signature in the presence of two witnesses.

FRANKLIN S. MARR.

Witnesses:

ANNA LINERS,
H. E. HARTER.
